UNITED STATES PATENT OFFICE

109,434

DESIGN FOR A COAT

Irving Cohen, New York, N. Y.

Application April 2, 1938, Serial No. 76,240

Term of patent 3½ years

To all whom it may concern:

Be it known that I, Irving Cohen, a citizen of the United States and residing in Manhattan, in the city, county, and State of New York, have invented a new, original, and ornamental Design for a Coat, of which the following is a specification, reference being had to the accompanying drawing, forming part thereof.

Fig. 1 is a front view of a coat showing my new design.

Fig. 2 is a rear view thereof.

Fig. 3 is a fragmentary view of Fig. 1 in open position with the belt portion untied.

The flowers are permanently attached.

I claim:

The ornamental design for a coat, substantially as shown and described.

IRVING COHEN.
